DOWNSPOUT SPLASH BLOCK

Bruce A. Littman, Highland Park, Ill., and Robert O. Memmel, Okauchee, and Jack B. Waldheim, Mequon, Wis., assignors to Benson Mfg. Corporation, Menomonee Falls, Wis.

Filed Apr. 24, 1972, Ser. No. 247,260

Term of patent 14 years

Int. Cl. D25—01

U.S. Cl. D18—2 A

FIG. 1 is a top and front perspective view of a downspout splash block showing our new design.

FIG. 2 is a rear and top perspective view of a downspout splash block showing our new design.

FIG. 3 is a top plan view of FIG. 2.

FIG. 4 is a side elevational view partially in section taken along line 4-4 of FIG. 3.

The broken line showing of a downspout in FIG. 4 is for illustrative purposes only and forms no part of the design.

We claim:

The ornamental design for a downspout splash block, as shown.
